(57) **CLAIM**

The ornamental design for a rear spoiler for an automobile, as shown and described.

DESCRIPTION

FIG. 1 is a first side perspective view of a rear spoiler for an automobile in accordance with our new design;

FIG. 2 is a second side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The mounting surfaces of the rear spoiler, shown in broken lines in FIGS. 4 and 6 form no part of the claimed design since these surfaces are hidden when the rear spoiler is mounted to the automobile.
